UNITED STATES PATENT OFFICE.

CLAUDE A. CONOVER, OF NEWBURGH, NEW YORK.

GARMENT-PROTECTOR.

1,229,890.

Specification of Letters Patent. Patented June 12, 1917.

Application filed June 3, 1916. Serial No. 101,475.

To all whom it may concern:

Be it known that I, CLAUDE A. CONOVER, a citizen of the United States, and a resident of Newburgh, in the county of Orange and State of New York, having invented certain new and useful Improvements in Garment-Protectors, of which the following is a specification.

My invention relates to the protection of clothing when not in use, and the main object thereof is to provide a container which may be adapted for use with evening or holiday clothing, or which may be adapted for the protection of clothing against moths during the summer months.

My invention is of the bag type and, while I am aware that protectors of this type are now in use, my protector presents certain novel features over any now known to me, both as to structure and as to the facility in placing clothing therein.

My invention is fully described in the following specification, of which the accompanying drawings form a part, in which like characters refer to like parts in each of the views, and in which:—

Figure 1 is a closed view of my protector in use, partly broken away;

Fig. 2 is a view thereof open and showing the manner of placing clothing therein or removing the same therefrom;

Fig. 3 is a view similar to Fig. 2 but showing a modification thereover;

Fig. 4 is a bottom end view of the protector, fragmentarily; and

Fig. 5 is a detached view of an upper frame which I employ to hold the protector in shape and to serve as a support for depending garment hangers.

The protector consists primarily of a bag 6 oblong in form and composed of either fabric, paper, or other suitable material of a flexible or foldable nature, said bag being open at its top though adapted to be closed by a drawstring 7.

Attached to opposite sides of the bag 6, at points on a plane well above the bottom of the bag, as shown at 8 Fig. 2, are fabric strips 9 secured at their upper ends to a frame 10 shown as of wire bent to provide a rectangular portion 11 and longitudinally arranged bars 12, and said frame is adapted to be suspended from a rod 13 or hook or suitable equivalent within a closet by means of a looped member 14 connected with the corners of the frame 10 by means of strips 15.

When the drawstring 7 has been released and the open top of the bag expanded the portion of the bag above the lines of stitching 8 may drop to give access to the space between the strips 9 and to the frame 10 whereby clothing may be suspended from the latter or may be readily removed therefrom, the strips 9 being preferably made of a length equaling or approximating the 60 lengths of skirts, dresses, pants, overcoats, and the like, according to the particular use to which the protector is to be put, and I will in all probability market the protectors in standard sizes, and of materials adapted to different uses.

When the upper portion of the bag has been so dropped a box-like portion 16 is presented beneath the lines 8 of stitching and into which the bottoms of dresses, overcoats, etc. may be easily placed and these bottoms of garments will not thereafter interfere with the upward movement of the upper portion of the bag in the act of closing the same, this constituting a highly important feature of my protector in view of the practical inability to successfully drape clothing in bags of this type to prevent the wrinkling thereof.

In Fig. 3 I have shown the full equivalent of the form already described with the difference that I provide cords 17 as a substitute for the strips 9 and 15 and I also provide a frame 18 in the plane of the lines 8 of stitches in the form shown in Figs. 1 85 and 2, this last named frame positively 90 insuring the box-like lower bag portion 16 for the reception of the bottoms of the garments preparatory to closing the protector.

My protector may be readily collapsed 95 to occupy very little room, as for storage, transportation, etc., and the cost thereof over the conventional types now in use will be inconsiderable.

While I have shown two distinct embodiments of my invention, I do not desire to confine myself thereto but may make changes thereover providing, however, that the box-like portion 16 is presented, when the upper bag portion is dropped, for the reception 105 of the bottoms of clothing previous to drawing the collapsed bag portion upwardly over the frame 10.

Having fully described my invention, what I claim as new, and desire to secure by Letters Patent, is:—

1. A garment protector, comprising a bag

- open at its top, a drawstring therefor, a frame in the upper portion of said bag, means for suspending said frames, a frame intermediate the height of said bag, adjacent its bottom, means joining said frames, and means for permanently securing the lower frame to said bag, said bag presenting a box-like lower portion below said lower frame when the upper bag portion has been dropped to permit arrangement of the lower portions of garments suspended from the upper frame previous to drawing up the upper portion of said bag from its lowered position.

2. A garment protector, comprising a

bag open at its top, a drawstring therefor, 15 a frame in the upper portion of said bag, means for suspending said frame, a frame adjacent the lower end of said bag in permanent connection with said bag, and flexible strips joining opposite ends of said 20 frames, the lower portion of said bag below said lower frame presenting a box formation, when the upper bag portion has been dropped, for arranging the lower portions of garments suspended from said upper 25 frame previous to drawing up said lowered portion of said bag to inclose the garments.

CLAUDE A. CONOVER.
